UNITED STATES PATENT OFFICE.

MILLER W. OTTO, OF AURORA, ILLINOIS, ASSIGNOR TO THE LARIMER COMPANY, OF AURORA, ILLINOIS.

AUTOMATIC DOOR CLOSER.

Application filed May 2, 1927. Serial No. 188,298.

My invention relates to automatic door closers wherein spring means is employed for closing the door and pneumatic means is employed for cushioning the said closing operation.

An object of the invention is to provide a simple, inexpensive and durable device of this character which is of compact construction having a pneumatic chamber and a spring 10 housing in one unit.

Referring to the drawings, which are made a part hereof and in which similar reference characters indicate similar parts,

Figure 1 is a side elevation illustrating a 15 device constructed in accordance with my invention and showing the same applied,

Figure 2, a top plan view,

Figure 3, an end elevation,

Figure 4, an end elevation illustrating a 20 different method of mounting the device,

Figure 5, a central horizontal section,

Figure 6, a side elevation with part of the casing broken away,

Figure 7, a perspective of a crank shaft, 25 and

Figure 8, a section taken on the line 8—8 of Fig. 6.

In the drawings reference character 10 indicates a housing or casing having a removable closure plate or cover 11 provided with a centrally disposed boss or bearing member 12 which forms in conjunction with a ratchet sleeve 13 disposed in a central bearing member or boss 14 in the opposite side of the casing, a bearing for a shaft 15. The shaft 15 is flattened at its upper and lower ends 16 and 17 respectively for reception of one arm 18 of a toggle lever, which comprises pivotally connected arms 18 and 19, the other arm 19 30 of which is adapted to be connected to a member such as a door 22 movable relatively to a support or door frame 24 upon which the casing or housing 10 is mounted so that when such relative movement occurs the shaft 15 35 will be given a partial rotation.

The casing 10 is provided with a bracket 20 having apertures 21 for fastening screws or the like for attachment of the casing directly on a door 22, as shown in Fig. 4, or upon a 40 bracket or foot 23 as shown in Figs. 1 to 3. In order to mount the parts in a different position with the casing 10 supported on the door frame and with the foot or bracket 23

of the lever 19 pivoted to the door, I provide a flush soffit or bracket 25 which has one end 55 for connection with the door frame and has its other end of a shape corresponding to the bracket 20 of the casing 10 by means of which said bracket 20 and its casing may be supported.

With the device mounted as above described, the shaft 15 will be rotated with each movement of the door relative to its supporting frame and in order to cause the door to close, I provide a spring 26 for performing 60 this function. The spring 26 comprises a substantially flat band wound upon itself and having a hook 27 formed at its inner end for engagement in a longitudinally disposed slot 28 in the ratchet sleeve 13 and having a hook 70 formed at its outer end for engagement with a slot 29 in the inner wall of the casing 10. In order to tension the spring, the ratchet sleeve 13 is provided on its outer end with a ratchet 30. A plate 31 has a slot corresponding in 75 shape to the flattened end 17 of the shaft 15, and the outer end of such plate has pivoted thereon a pawl 32 for engagement with the teeth of the ratchet 30 when the same is rotated to tension the spring so that the shaft 80 will be held in a fixed position relative to the casing in which it is supported. When the device is applied and the door is opened the spring will set to close the door.

The important feature in conjunction with 85 this is the plate 31 being in a fixed position on the end of the shaft 16 and next to the ratchet 30. This eliminates the changing of the spring or any of the parts for right or left, hinge or jamb side doors. This is made 90 possible on account of plate assembly 31 being in a fixed position on shaft 16 and next to ratchet 30, which is engaged with the spring and with pawl 32 engaged in ratchet 30. The tension of the spring is provided by winding 95 the ratchet which is wound always in the same direction for both right and left hand doors. Another feature in connection with the same is that the spring or eccentric shaft 16 moves always in the same direction regardless of 100 which end of the shaft arm lever it is attached. In order to cushion the closing operation of the door, a cylinder 33 is provided having one 105 end closed by means of a cap 34 and in which is disposed a piston 35 connected by means of a connecting rod 36 with a crank 37 on the

shaft 15. The cylinder 33 is threaded or otherwise detachably secured in the casing 10 and the cap 34 is threaded or otherwise secured on the opposite end of the cylinder. 5 The piston 35 comprises a steel cup against the back of which is supported an oppositely disposed cup leather or piston packing 38 held by means of a piston bolt 39 in engagement with the piston 35, such piston bolt being 10 provided with washers 40 and 41 held in place by a nut 42.

The piston bolt 39 is disposed axially of the cylinder 33 and in order to insure the maintenance of such piston in proper position, I 15 provide a piston guiding washer or element 43 on the piston bolt 39 and secure the same thereon by means of a nut 44. A spring expander 45 is provided for holding the cup leather or piston packing 38 evenly or 20 smoothly against the inner wall of the cylinder, such spring expander being disposed between the guiding washer 43 and the piston packing. When the piston is moved toward 25 the end of the cylinder upon which is mounted the cap 34, air will be entrapped in the end of such cylinder and prevent a sudden action of the spring.

An air check regulating screw 46 is disposed in the cap 34, such screw having a tapered flattened side which, when the screw 30 is moved longitudinally, controls the escape of air from the cylinder 33. A lock nut 47 is provided for securing said adjusting screw in fixed position.

In order to allow sufficient air to enter the cylinder when the piston is moved away from the cap 34 I provide such cap with a valve 48 which has a head provided with a leather packing adapted to seat against the inner surface of the cap and having a stem with flat surfaces which permit air to be drawn into the cylinder upon the backward travel of the piston, such valve being closed by compression upon the forward travel of the piston.

45 The concentric shaft 15 is of a peculiar shape designed to permit the crank 37, formed preferably integral therewith, to travel sufficiently to permit a full stroke of the piston and in order to permit such action, the shaft 50 is provided with an eccentric 49 having a slot or recess 50 therein in which the connecting rod 36 is adapted to be disposed when the door is open and the piston is in a position opposite that shown in Figs. 5 and 6.

55 In order to provide means for holding the shaft 15 in a fixed position with the door open, I provide a brake or friction plate 51 secured at one end by means of a screw 52 in the casing 10 and with its free end disposed in a position 60 so that the crank 37 will pass over the same. In order to cause the plate 51 to frictionally engage the crank 37, an adjusting screw 53 is provided. This adjusting screw may be screwed into the casing against the 65 plate 51 to raise the plate to frictionally en-

gage the crank 37 when it reaches the desired position of holding open the door. When the door is held open by the friction plate, by giving it a slight push it will close under the action of the spring 26.

70 It will be obvious to those skilled in the art that various changes may be made in my device, without departing from the spirit of the invention, and I, therefore, do not limit myself to what is shown in the drawings and 75 described in the specification, but only as set forth in the appended claims.

Having thus fully described my invention, 80 what I claim as new and desire to secure by Letters Patent is:

1. A combined door closer and check comprising a casing, a cylinder communicating with said casing, a shaft disposed within said casing, a crank arm in said casing on said shaft, an eccentric on said shaft at one side 85 of the crank arm and provided with a slot to permit the operation of the crank arm through an angle of 180°, a spring coiled about said shaft and having one end engaging said casing and its opposite end connected with the shaft, a piston in said cylinder and a pitman connecting said crank arm and piston, substantially as set forth.

2. An automatic door closer comprising a casing, a shaft mounted in said casing and 95 provided with an eccentric intermediate its ends, a crank arm at one side of said eccentric, a cylinder associated with said casing, a piston in said cylinder, a pitman connecting said crank arm and piston, said eccentric being 100 provided with a slot to permit said crank arm to move with said pitman from one position to a diametrically opposite position, spring means tending to maintain said shaft in a predetermined position and a friction brake 105 for engaging said crank arm for maintaining the same in fixed position, substantially as set forth.

3. In a door closer the combination of a 110 casing, means rotatable within said casing, lever mechanism for connecting said rotatable member and a door, spring means tending to rotate said rotatable member for closing the door, and a friction plate mounted in said casing and adjustable to a position to engage 115 the rotatable member to prevent its operation, substantially as set forth.

4. An automatic door closer comprising a 120 casing, a shaft mounted in said casing and having its ends projecting therefrom, a connection for attachment with either end of said shaft, and to a door, spring means for rotating said shaft in one direction, an eccentric on 125 said shaft and a connection between the shaft and eccentric permitting the shaft to be rotated through an angle of substantially 180 degrees, substantially as set forth.

5. An automatic door closer comprising a 130 casing, a shaft mounted in said casing and having its ends projecting therefrom, a con-

nection for attachment with either end of said shaft, and to a door, spring means for rotating said shaft in one direction, an eccentric on said shaft, a connection between the shaft and eccentric permitting the shaft to be rotated through an angle of substantially 180 degrees, and an adjustable friction

plate for engaging and holding the eccentric in fixed position, substantially as set forth.

In witness whereof, I have hereunto set ¹⁰ my hand at Aurora, Illinois, this 28th day of April, A. D. nineteen hundred and twenty-seven.

MILLER W. OTTO.
